AUDIENCE SEAT

James H. Adamson, Larchmont, N. Y.

Original application December 14, 1932, Serial No. 647,155. Divided and this application April 13, 1934, Serial No. 720,356

3 Claims. (Cl. 155—130)

This invention relates to movable audience seats and particularly one adapted for use in gymnasias or other fully or partially enclosed spaces.

5 It is the object of the present invention to provide an audience seat of the bleacher type which can be readily moved out of the way against the wall without the necessity of providing guides on the wall, which is light and yet sturdy in construction, and the seats and footrests of which can be readily removed and locked against displacement.

This application is a division of Serial No. 647,155, filed December 14, 1932.

15 In the drawing Fig. 1 is a side elevation of the audience seat;

Fig. 2 is a perspective view of the connecting and locking arrangement by means of which removable seat sections may be joined with the permanent sections;

20 Fig. 3 is a sectional view along line 3—3 of Fig. 2; and

Fig. 4 is a sectional view along line 4—4 of Fig. 3.

25 Referring now to the drawing, 1 and 2 are wooden seats and footrests, respectively. There are as many seats as is required, and they are fastened to substantially C-shaped steel tubes 3, which in turn are riveted or welded to steel tubes

30 or stringers like 4. The stringers 4 are provided in pairs and the number of stringer pairs is dependent on the length and seating capacity of the structure. The upper side of each pair of

35 stringers 4 terminate in a pair of brackets like 5. Within the brackets 5 is rotatably mounted a rubber caster 10. In the open position of the bleacher the caster rests on an arm 11 pivoted to the wall 14.

The stringers may be moved up and down by 40 means of rope 8 led over a pulley 17 fastened to the wall 14 and through other pulleys to balancing weights (not shown). Similarly, ropes are fastened to the other sets of stringers like 4.

45 The lower ends of each pair of frame members or stringers 4 terminate in casters like 34 resting on the floor 15.

In the open position of the seat a rod 47 may be locked between the floor 15 and the bracket holding the caster to insure stability. When this rod 47 and other similar bars that may be placed are removed, the stringers 4 may be grasped near the bracket 5 and moved upward until the seat assembly is in a position substantially parallel with the wall of the gymnasium.

The rubber casters like 10 will roll on the wall or a channel mounted on the wall.

In gymnasias or other places where such movable seats are used, the permanent obstruction of certain portions of a wall is sometimes objectionable. Those portions of the seats and footrests 1 and 2 which would normally obstruct a door or the like are sawed out and, when required, the sawed-out portions are filled in with detachable seat and footrest sections like 50 (Figs. 2-4). 10 In order to permit quick and firm attachment of the movable sections 50, their secure locking in place and ready removability, the following arrangement is provided:

An L-shaped steel angle plate 51 is fastened 15 near the edge of the detachable section 50 by means of bolts 52. The shorter leg 53 of the angle piece 51 has an ear 54 projecting from it at substantially right angles. This ear fits within a cut-out portion 55 in the vertical leg 56 of 20 an angle piece 57, fastened by means of bolts like 58 to the lower face of the seat 1 near the sawed-off edge thereof. When the detachable section 50 is put in place with the ear passing through opening 55, it will engage a nose 59 of 25 locking bar 60 and swing it to the right (as viewed in Fig. 4) around its pivot point 61 in the leg 56 of the lower angle piece 57. When the projection 54 reaches the bottom of the cut-out 30 55 and the leg 53 rests on the angle piece 57, the lock 60 swings by its own weight back into the vertical position, locking the detachable section 50 against displacement. When it is desired to 35 remove the detachable section the lock 60 is swung by hand into the dotted line position (Fig. 4), whereupon the section 50 may be removed.

What I claim is:

1. In an audience seat, a plurality of stringers, a plurality of seat and footrest members permanently fastened to said stringers, a movable seat section, an angle piece attached to the edge of said seat section and having an ear projecting from one leg, a second angle piece attached to a permanently fastened seat section and having an opening to receive said ear, said angle pieces having vertically projecting legs spaced from the seat sections to which the angle pieces are fastened and interfitting to prevent lateral displacement of adjacent seat sections, and a bar pivoted to said second angle piece and having a locking nose projecting within said opening. 40

2. In an audience seat, a plurality of stringers, a plurality of seat and footrest sections permanently fastened to said stringers, a removable seat section, a first angle piece, means for attach- 45 50 55

ing said piece to the edge of said removable seat section, a second angle piece, means for attaching said second piece to a permanently fastened seat section, said second piece having an opening to receive an ear of said first angle piece, said angle pieces having vertically projecting legs spaced from the seat sections to which the angle pieces are fastened and interfitting to prevent lateral displacement of adjacent seat sections, and a bar pivoted to one of said angle pieces for locking said ear within said opening.

3. In an audience seat, fixed and movable seat sections, each having an angle piece at their ad-

5 jacent edges, each angle piece having one leg flatly secured on opposite faces of the seat sections and the other leg spaced from the corresponding edge of the seat section, said other legs extending opposite to one another, the other angle piece leg on the movable seat section having a longitudinally extending ear fitting into an opening in the other angle piece leg of the fixed seat section, and a pivoted bar on the last mentioned leg and having a locking nose projecting within said opening and engaging said ear.

5

10 JAMES H. ADAMSON.
